FOREIGN PATENT DOCUMENTS

FR 2598182 A1 11/1987

Primary Examiner — David Muller
Assistant Examiner — Nathan Johnston(57) **CLAIM**

The ornamental design for a cassette, as shown and described.

DESCRIPTION

FIG. 1 is a front perspective view of a cassette;

FIG. 2 is a front elevation view thereof;

FIG. 3 is a right side elevation view thereof;

FIG. 4 is a left side elevation view thereof;

FIG. 5 is a rear side elevation view thereof;

FIG. 6 is a top plan view thereof; and,

FIG. 7 is a bottom plan view thereof.

The dash dot lines immediately adjacent to the claimed areas in FIG. 7 represent the boundaries of the claimed design. The dashed lines in the figures illustrate the portions of the design that form no part of the claimed design. None of the broken lines form any part of the claimed design.

1 Claim, 6 Drawing Sheets---
